US0D1079691S

(12) **United States Design Patent** (10) **Patent No.:** **US D1,079,691 S**
(45) **Date of Patent:** ** *Jun. 17, 2025

(54) **SMART WATCH**

(71) Applicant: **Fitbit, Inc.**, San Francisco, CA (US)

(72) Inventors: **Benjamin Patrick Robert Jean Riot**, San Francisco, CA (US); **Cédric Eric Jean-Edouard Bernard**, San Francisco, CA (US); **Chadwick John Harber**, San Francisco, CA (US); **Brian Dennis Paschke**, San Francisco, CA (US); **Derek Jenchia Loh**, San Francisco, CA (US); **Eric John Fairbanks**, Pleasant Hill, CA (US); **Mark Woolhisler Huang**, San Francisco, CA (US); **Jonah Avram Becker**, San Francisco, CA (US)

(73) Assignee: **Fitbit, Inc.**, San Francisco, CA (US)

(*) Notice: This patent is subject to a terminal disclaimer.

(**) Term: **15 Years**

(21) Appl. No.: **29/878,142**

(22) Filed: **Jun. 16, 2023**

Related U.S. Application Data

(60) Continuation of application No. 29/746,956, filed on Aug. 18, 2020, now Pat. No. Des. 1,007,504, which is a division of application No. 29/706,974, filed on Sep. 25, 2019, now Pat. No. Des. 903,664.

CLAIM

The ornamental design for a smart watch as shown and described.

DESCRIPTION

FIG. 1 is a top, right side isometric view of a smart watch, showing our new design.

FIG. 2 is a bottom, right side isometric view thereof;

FIG. 3 is a front side elevation view thereof;

FIG. 4 is a back side elevation view thereof;

FIG. 5 is a left side elevation view thereof;

FIG. 6 is a right side elevation view thereof;

FIG. 7 is a top side plan view thereof; and,

FIG. 8 is a bottom side plan view thereof.

The broken lines in the drawings illustrate portions of the smart watch and form no part of the claimed design. The dash dot dash broken lines in FIGS. 2-6 and 8 represent a claim boundary and form no part of the claimed design.
